[57] CLAIM

The ornamental design for a travel enclosure for a golf club bag, as shown and described.

DESCRIPTION

FIG. 1 is a perspective view showing the top, right side and front of a travel enclosure for a golf club bag which forms my invention;

FIG. 2 is a top plan view thereof;

FIG. 3 is a front elevational view thereof;

FIG. 4 is a right side elevational view thereof, this view and the opposite left side elevational view being of identical design;

FIG. 5 is a rear elevational view thereof; and,

FIG. 6 is a bottom plan view thereof.
